MITER BOX

William J. Parsons, Millers Falls, Mass., assignor
to Millers Falls Company, Greenfield, Mass., a
corporation of Massachusetts

Application May 11, 1937, Serial No. 141,884

4 Claims. (Cl. 143—86)

The present invention provides certain improvements in the construction of miter boxes. More particularly, the present invention provides an improved and simplified construction of clamping instrumentalities for stock to be sawed and means for mounting such instrumentalities whereby the clamping and releasing of the stock is greatly facilitated, together with improved construction of the saw guides.

10 In accordance with the present construction, clamping means for the stock to be sawed are provided, which clamping means are quickly adjustable and which are carried in novelly shaped and novelly mounted brackets which facilitate the quick adjustment of the clamping means; and one of the objects of the invention is to provide such brackets which are mounted in such a manner that they may be shifted freely and very easily between operative and inoperative positions.

15 A further object of the invention is to provide locking means for the brackets, which locking means are self-actuating responsive to the brackets assuming operative position, so as to secure the brackets in such position while being instantaneously releasable for enabling the brackets to be released for adjustment or other desired purpose.

20 A still further object of the invention is to provide mounting means for the brackets for enabling adjustment of the brackets longitudinally of the base support for accommodating the clamping instrumentalities to any length of stock which is to be cut.

25 A still further object of the invention is to provide clamping instrumentalities for the stock, which instrumentalities are pivotally mounted in the said brackets and which are adapted to either a quick or slow adjustment selectively relative to the stock.

30 A still further object of the invention is to provide mechanism for mounting the said clamping instrumentalities in the brackets while permitting the aforesaid quick or slow adjustment 35 of the clamping instrumentalities responsively to the selection of the operator.

35 A still further object of the invention is to provide improved saw-guide construction which permits the ready insertion of the saw-frame supports, which also are constructed novelly for the retention of the saw frame, the said saw-guides being provided with means for preventing accidental displacement of the saw-frame supports therefrom.

40 A still further object of the invention is to pro-

vide improved locking instrumentalities for securing the radius bar in any desired angular position relative to the base support.

45 Further objects and advantages of the present improved construction will appear hereinafter, the novel features and combinations being set forth in the appended claims; and the invention accordingly comprises the features of construction, combination of elements, and arrangement of parts, which will be exemplified in the construction hereinafter set forth, and the scope of the application of which will be indicated in the claims.

50 The invention will be understood from a consideration of the following detailed description, taken in conjunction with the accompanying drawings which show details of the improved construction in a typical embodiment thereof, it being obvious that mechanical expedients other than those disclosed may be adopted, so that the drawings, therefore, are not to be taken as being restrictive in character.

55 In the accompanying drawings, Fig. 1 is a front elevation of the improved miter-box, the view including the clamping instrumentalities for holding the stock in position for sawing operations, the stock being either metal or wood. The view indicates also certain details of the mounting of the clamping instrumentalities enabling their adjustment along the base of the miter-box for accommodation to any length of stock being sawed.

60 Fig. 2 is a rear elevation of the miter box of Fig. 1.

65 Fig. 3 is a plan view of one-half of the miter-box, including the adjustable carriage for the saw and one of the quick-acting clamps for holding the stock in position.

70 Fig. 4 is a sectional elevation of the miter-box taken on the line 4—4 of Figs. 1, 2 and 3 looking in the direction of the arrows and showing certain details of one of the quick-acting clamps and its point of anchorage to the miter-box.

75 Fig. 5 is a sectional plan view through the swivel joint of one of the quick-acting clamps, the view being taken on the line 5—5 of Fig. 4, looking in the direction of the arrows, and showing details of one form of mechanism which may be employed for adapting the clamping screws for either quick or fine adjustment relative to the stock being sawed.

80 Fig. 6 is a vertical section through the releasable self-actuating locking means for the mounting brackets for the clamping screws, the view

being taken generally on either of the lines 6—5 of Figs. 1 and 2.

Fig. 7 is a detail view, partly in section, of the joint on the end of the clamp screw and the cup holding the clamp pad that contacts the surface of the stock to be cut.

Fig. 8 is a view partly in section and partly in elevation of certain of the details of construction, the view being taken on the line 8—8 of Fig. 3 and showing a side elevation of the front part of the adjustable carriage for the saw and a vertical section through the rear part of the said carriage showing certain details of the locking mechanism for the said carriage.

Fig. 9 is a view similar to Fig. 8, but showing a side elevation of the rear part of the carriage for the saw and a vertical section through the front part of the carriage, the view being taken on the center line of the carriage, indicated at 9—9 on Fig. 3 looking in the direction of the arrows.

Fig. 10 is a front elevation of the adjustable saw carriage, the view being taken on the plane of the line 10—10 of either Fig. 8 or Fig. 9, looking in the direction of the arrows.

Fig. 11 is a vertical section through the saw carriage, taken on the line 11—11 of either Fig. 8 or Fig. 9, looking in the direction of the arrows.

Fig. 12 is a vertical section through the saw carriage, taken on the line 12—12 of either Fig. 8 or Fig. 9, looking in the direction of the arrows.

Fig. 13 is a vertical section through the saw carriage, taken on the line 13—13 of either Fig. 8 or Fig. 9, looking in the direction of the arrows.

Fig. 14 is a vertical section through the saw carriage, taken on the line 14—14 of either Fig. 8 or Fig. 9, looking in the direction of the arrows.

Fig. 15 is a plan view of the locking stud lever for the radius bar of the saw carriage, showing the hole used to attach the lever to the locking stud and the slot at the opposite end for the locking rod.

Fig. 16 is a view partly in section and partly in elevation of a locking pin employed in the support for the saw frame, showing the construction of the locking pin.

Fig. 17 is an end view of the locking pin of Fig. 16.

Fig. 18 is a front elevation of one of the supports for the saw frame and a stop for the frame.

Fig. 19 is a side elevation of the parts shown in Fig. 18.

Fig. 20 is a top plan view of the parts illustrated in Figs. 18 and 19.

Before proceeding with a detailed description of the invention, it may be mentioned that the improved miter box assembly of the present invention comprises, generally, a base for receiving the work or stock to be sawed, a pair of adjustably mounted brackets each carrying a quick action clamp for engaging the said stock, and an adjustable carriage to hold, guide and control the position of the saw, the said carriage including improved mechanism for positively locking the carriage in adjusted position, and which prevents accidental release of the carriage from its adjusted position.

Referring more particularly to the drawings, it will be seen that the construction includes an angle box, indicated generally by A, which is used to support the work to be cut, the saw carriage assembly being indicated generally by B, the quick action clamps for holding in the angle box B the work to be cut, being indicated generally

by C, while D designates generally the lock pin assemblies for the supports for the saw frame.

The angle box assembly A comprises a frame 25, which is a substantially rectangular frame braced by rectangular reinforcing braces 27 which are welded to the frame 25, the frame 25 being braced also by diagonal braces 29 which are also welded to the frame. Secured to the frame 25 is a curved locking bar 31, which is generally semicircular in shape, and which is provided with attachment flanges 32 by which the locking bar is attached to the frame 25 by means of suitable bolts such as indicated at 34.

The frame is supported by leg units 33, which are formed in any suitable manner, conveniently from band stock which is bent to produce the front and rear legs, each of the leg units extending transversely across the frame 25 on the underside thereof and which are welded to the frame.

The frame 25 carries a pair of table plates 35, 35, these plates having their adjacent edges at a sufficient angle to each other so as to enable the saw carriage to operate between the plates and be adjusted to an angular position of at least 45° on each side of the center line. The table plates 35, 35 rest upon spacers 37, each of which spacers extends continuously around and beneath the respective plates 35, the latter being held in place on the spacers 37 and frame 25 by means of clamping hooks 39 which are anchored in the plate 35 and extend around the frame members 27, 29 and 31.

An upstanding corrugated back plate 41 is bolted to the frame 25 by means of the bolts 34 previously described, and additional bolts 36 which pass through the corrugated plate and into the frame 25, which is provided with tapped holes for this purpose.

Adjacent to each end of the miter box assembly is a clamping assembly, designated generally by C, each of which is of identical construction, so that only one of these assemblies needs to be described in detail. Each clamping assembly C comprises an arm 43, which may be a drop forging, which is bent to form a pivot section 38 which is hinged on a pivot pin 45 extending longitudinally of the miter box behind the corrugated plate 41, the pin 45 being mounted in supports 47 which are secured to the corrugated plate 41 by means of screws 49. The arm 43 is turnable freely about the pin 45 and is slidable along the pin so as to be adjustable for any length of stock to be cut.

The arm 43 includes also a bend 40 at which is mounted a clamping screw 61, which will be described in detail hereinafter. The bend 40 in the arm 43 produces a bow in the arm which provides effective resistance to clamping stresses communicated to the arm 43 through the screw 61, as well as providing a proper shape to the arm 43 for enabling the arm to engage the plate 35 when the arm is in secured position. This engagement is effected in the region of the free end 42 of the arm 43, which end is shaped and recessed to form a housing 48 (Fig. 6) in which is inserted a lock pin 51 which is retractably mounted in the housing 48 and which is held normally in expanded or locking position by means of a spring 53, which encloses a shank 42' of the pin 51 and which is compressed between the shoulder 44 of the pin and the internal shoulder 46 of the housing 48. A handle or knob 55 is threaded on the end of the shank 42' of the pin 51, this handle knob retaining the pin 51 in its housing 48.

and also providing means whereby the pin may be retracted against the pressure of the compressed spring 53 so as to withdraw the pin 51 from its engagement with the frame 25, thus releasing the arm 43 for enabling the latter to be swung about the pivot pin 45, or moved along the pin for adjustment of the position of the arm 43.

The work to be cut is inserted in the miter box on the base plates 35, 35 by releasing and raising the arms 43 in the manner described above, and when the work is in proper position for cutting operation, the arm is dropped back into position, whereupon the lock pin 51 first strikes against the frame 25 so as to compress the spring 53 until the pin 51 is enabled to clear the frame 25. When this occurs, the spring 53 expands the lock pin 51 back into locking position, whereby the arms 43 become again rigidly secured in locking position.

It has been said that a clamp screw 61 is mounted at the bend 40 of each of the arms 43. For this purpose, a holder 71, which will be described in detail hereinafter, is mounted in the arm 43, the screw 61 passing through this holder. The clamp screw 61 is operated by turning its handle knob 59, which forces a work-contact pad 63, mounted on the lower end of the screw 61, against the work to be cut, by transferring pressure exerted on the screw 30 through a ball connector 65 (Fig. 7) on the end of a cup 67 and a socket 69 in the lower end of the clamp screw 61. This ball joint connection for the pad 63 enables a firm clamping action to be had on any piece of work regardless of the 35 shape thereof, since the engagement of the pad with the work is conformable freely to the shape thereof responsively to pressure exerted by the screw 61.

The screw 61 is adapted to be quickly adjusted relative to the work, by in and out movement as designated by the arrow 62 in Fig. 4. In order to obtain this quick motion, a special mounting mechanism is provided which includes the holder 71, which has been mentioned previously above.

In order to accommodate this holder, the bend 40 of the arm 43 is provided with a bifurcated enlargement 72 (Fig. 5) which is apertured to receive a sleeve 71 which is inserted in openings 85 provided in lugs 74 formed one on each section of the enlarged portion 72 of the arm 43. This sleeve 71 is apertured to permit the clamp screw 61 to pass freely crosswise through it and is closed at one end and forms a housing for receiving a spring 79 which is compressed between the end of the sleeve 71 and the holder 71, as will be apparent from Fig. 5. The holder 71 therefore constitutes a spring pressed plunger or piston which has a hole 75 therethrough for receiving the clamping screw 61.

This hole 75 is of a generally elliptical shape, as will be seen from Fig. 5, and it is provided with internal threads 73 which engage the clamping screw 61, the threads 73 being a half section of a full thread, the other half of the hole 75 being unthreaded, the configuration of the hole providing a clearance between the smooth or unthreaded portion of the hole and the clamping screw 61, so that when pressure is applied to the end of the plunger 71 of sufficient magnitude to overcome the pressure of the spring 79, the plunger 71 is moved inwardly so as to clear the engagement between the threads 73 of the hole 75 and the clamping screw 61, thus releasing the latter for free sliding movement

through the hole to give a quick adjustment of the clamping screw relative to a piece of work to be cut. The movement of the plunger 71 is indicated clearly by the arrow 80 in Fig. 5.

When the parts are in the position indicated in Fig. 5, the clamp screw 61 is not free for a quick adjustment thereof relative to the work, but it is held by the thread 73 and can be advanced or retracted relatively to the work only by a turning movement of the screw, which provides for a fine adjustment of the clamping screw; while, when the screw 61 is released by pressure applied to the plunger 71 so as to overcome the force of the spring 79, the threads 73 are moved out of engagement with the threads on the clamp screw, so that the latter is released for quick movement incident to the disengagement of the threads as aforesaid.

A safety catch for plunger 71 may be provided, such as pin 81, set in plunger 71 and slidably therewith in slot 83 which is sufficiently long to allow sufficient movement to the plunger to engage and release pin 61. An opening 87 is provided in the arm 43 for enabling angular adjustment of the clamp screw 61 about the center 25 of the sleeve 71.

With this arrangement of the quick acting clamp, work parts in the form of irregular cross sections, such as, for instance, metal or wood molding, may be quickly clamped in position in the miter box.

Reference may now be made to the supporting assembly for the saw.

This assembly is indicated generally by the character B, and includes a front support 89 and a rear support 91 which are adapted to receive the saw frame, indicated generally at 92. These supports 89 and 91 are carried by the saw frame which passes through slots 93 and 95 provided for this purpose in the supports 89 and 91, the saw frame 92 sliding back and forth in these slots.

The slots 93 and 95 are provided in an enlarged head portion 96 of the supports 89, 91, the remainder of these supports being of a more restricted diameter and being in the form of an elongated rod adapted to be inserted in the tubular holders 113, 115, which will be mentioned in greater detail hereinafter.

The saw frame 92 is held in the slots 93 and 95 by spacers 97 and 99 which are inserted in the upper part of the slots, and which become flush with the periphery of the supports 89, 91, when properly inserted. These spacers 97 and 99 are held in the supports 89 and 91 by means of a screw 107, which secures the spacers in position and positively retains the saw frame in the slots 93 and 95 so that there is no possibility of accidental displacement of the saw frame from these slots.

The front and rear supports 89 and 91 are each provided with a stop 101 for controlling the low position of the saw blade, the stop 101 engaging the upper end of the tubular holders 113 and 115, respectively, when the saw frame and supports are mounted in operative position. The stops 101 are secured in their position of desired adjustment by means of a screw 105.

The sides of the slotted ends of the front and rear supports 89 and 91 are toothed at 103, shown in Figs. 18, 19 and 20, these teeth 103 matching the corresponding teeth formed on the end of the stop 101. This arrangement prevents the slipping of stop 101 when the screw 105 is tightened. It will be seen clearly from Fig. 19 that the stop 101 is provided with a longitudinal slot 75

- 102 which receives the screw 105, whereby when the screw 105 is released, the stop 104 is released so that it may be adjusted as desired relatively to the support.
- 5 A vertical slot 109 (see, for example, Figs. 10 and 11) is provided near the lower end of the front and rear supports 89 and 91 for the insertion of a saw blade 110, when the blade is clamped into the saw frame. The upper end of the slot 109 is made narrow, as indicated at 111 (see Figs. 8, 9 and 10, for example) to form a guide for the saw blade 110, the back of the saw blade being received in the restricted portion 111 of the slot, and is prevented thereby from buckling during 15 operation.
- The front support 89 is held in position by a holder 113, and the rear support 91 is received in holder 115, these holders being tubular for the reception of the supports. The holder 113 is supported on a bar 117 which forms a part 20 of the saw carriage assembly, and holder 115 is supported by a bar 119 which also forms a portion of the saw carriage assembly. The bar 117 is provided with a groove 121 on the under side 25 thereof, (see Figs. 11 and 13), and bar 119 is provided with a shoulder 123 which is adapted to fit into the groove 121, the bars 117 and 119 being held together in assembled relation by means of a screw 125 which passes through these bars.
- 30 This construction may be seen in Fig. 11, for example. The holders 113 and 115 are provided with a clearance slot 127 for allowing the saw to be dropped to its low position.
- For facilitating the handling of the saw when 35 placing work in the miter box, or when changing saw blades, locking pins D are provided near the top of the holders 113 and 115, so that when the saw frame is lifted, the supports 89, 91 lock with the pins to hold the saw in raised position.
- 40 The details of the construction of these locking pins are shown in Figs. 16 and 17. The pin proper, indicated at 129, is received in a housing 131, the pin 129 having a shank portion 130 which extends through an opening provided 45 therefor in the end of the housing, and which is threaded, as indicated at 132, for receiving a handle member 135, which is shown as being a knob threadedly attached to the pin shank 130.
- 50 The shank 130 defines an annular shoulder 134 with the pin 129, and the housing 131 is provided with an internal annular shoulder 136, there being a coil spring 133 compressed between the shoulders 134 and 136, thereby urging the pin 129 in extended position, retraction of the pin 55 for insertion of the saw frame supports in the tubular holders being effected by a pull on the handle 135 sufficient to overcome the pressure of the spring. The handle 135 also holds the pin in the housing 131.
- 60 The locking pin 129 is provided with a flat surface 137 which fits in a corresponding hole 138 formed in the end of the housing 131, thereby preventing turning of the locking pin in the housing. Additionally, the end of the locking pin 129 is provided with a bevelled shoulder 140, and a flat shoulder 140', which shoulders enable the locking pin to fit in an annular groove 142 (see Fig. 9) on the lower end of the frame supports 89, 91. Threads 139 are provided on the end of the locking pin housing 131, as is shown clearly in Fig. 16, for securing the pins in the tubular holders 113, 115.
- When the saw is operating on the work, or is 75 resting in its low position, the locking pins 129

ride against the surface of the respective supports 89, 91, because of the pressure of the spring 133 against the pin 129. It is obvious, therefore, that when the saw is raised to its high position the locking pins 129 will be forced automatically into the grooves 142 of the supports, thus causing the saw to be held in its high position while at the same time locking the saw against accidental removal from the holders 113, 115. When the saw is to be lowered or removed from the tubular 10 holders, the handle knobs 135 are pulled outwardly until disengagement is effected between the locking pins 129 and the grooves 142, thereby releasing the supports 89, 91.

Considering now the assembly making up the 15 adjustable saw carriage, it will be seen that this assembly includes the tubular holders 113, 115, and the bars 117 and 119 which have been referred to previously, this assembly being swivelly anchored to the frame 25 by means of a swivel 20 stud 144, (see Figs. 3, 8 and 9) which stud is received in a suitable hole extending through reinforcing bars 141 and 143 (see especially Fig. 3) which bars are welded to the frame 25. The stud 144 is fastened in the bar 119 by means 25 of threads 146 (Fig. 8) on the end of the stud 144, which threads engage with threads in a tapped hole 148, a set screw 145 (Fig. 9) being provided for locking the stud 144 in the bar 119.

Additional support for the saw carriage assembly is afforded by the provision of a clamp bar 149 which rests on the reinforcing bar 143 of the frame 25, and the arcuate locking bar 31. This clamp bar 149 is fastened to the bar 119 by means of a stud 151 which passes through a 35 slot 152 in the bar 117 (see Figs. 8 and 9), the stud 151 being secured in place by a screw 153 which enters the stud through the lower end thereof. Additional connection between the clamp bar 149 and the bar 119 is made by means 40 of a stud 155 which is held by means of a screw 157 passing through the bar 119 and into the stud as will be apparent from Figs. 8 and 9. A clearance groove 159 is provided in the clamp bar 149 for the teeth on the saw blade 110.

In addition to its supporting function, the 45 clamp bar 149 also functions as a support for the parts of the work being cut, on either side of the saw blade, preventing the said parts from binding the blade during sawing.

The mechanism for locking the saw carriage assembly is shown especially in Figs. 3, 8 and 9, this mechanism enabling the said assembly to be locked in any radial position within a 45° angle on either side of the center line of the miter box.

This locking mechanism for the saw carriage assembly includes a locking stud 161 which has a threaded end 162 entering the clamp bar 149, the stud 161 being swivelled in the bar 119 as will be seen clearly in Figs. 8, 9 and 14. Turning movement of the stud 161 is effected by means of a lever 163 which is secured to the stud 161 by means of a flat side shoulder 165 (see Fig. 14) on the stud 161, corresponding to a suitable hole 167 in one end of the lever 163 (see Fig. 15). A lock nut 169 holds the lever 163 against shoulder 164 of the stud 161. A washer 171 is provided on the stud 161 between the bar 119 and the lever 163 for avoiding frictional wear between these parts.

The lever 163 is operated by actuation of a rod 173 (Figs. 3, 8 and 14), which has one end, 174, formed so that it enters slot 175 in the lever 163. Washers 177 are provided on rod 173 on either side of the lever 163, the end, 174, of the rod 75

being headed over at 179 to hold the washers in place and to prevent disengagement of the rod from the lever. The rod 173 is supported in position by supports 181, 183, which are, conveniently, screw-eyes positioned in tapped holes in bar 119. The operation of this locking mechanism will be referred to hereinafter.

The carriage assembly B for the saw is adjustable to enable the saw to cut at angles up to 45° on either side of the center line, as has been indicated above. For this purpose, the arcuate locking bar 31 is provided with slots or notches 185 (Figs. 8, 9 and 12), which slots are engaged by a locking pin 187 which slides through a hole by 188 in the bar 119. The pin 187 is held in the locked position by the pressure of a spring 189 against a lever 191 (see Fig. 11). This lever 191 has its end slotted so that it straddles the pin 187 (Figs. 11 and 12), and rests in a groove 193 in the pin 187. The pin 187 is withdrawn from slot 185 by upward pressure exerted on the front end of a second lever 195 which engages the lever 191 on the under side of the latter, and which is provided with a slot 209. A stud 205 is riveted in the lever 191 and passes into the slot 209 to form a sliding support for the lever 195.

The bar 119 also holds a stud 197, which stud passes through a hole 199 in the lever 191 and through the slot 209 in the lever 195, this stud 197 carrying fulcrum pins 203, 204 for levers 191 and 195. The mounting of the levers 191 and 195 is such that a slight relative longitudinal movement therebetween is produced upon an exertion of sufficient pressure on the end of lever 195 to move this lever against the pressure of spring 189 so as to compress this spring and at the same time causing lever 191 to pull downwardly on the pin 187 because of the engagement of the lever 191 in the groove 193 of the pin 187, thereby disengaging the latter from its locking position in slot 185, so that the saw carriage mechanism may be adjusted to the desired angular position.

The design of the lever mechanism for actuating the locking pin 187 is such that there is no tendency of the locking pin 187 to bind in the hole 188, but the movement is always smooth and positive. This is due to the mounting of the levers 191 and 195 to permit the relatively slight movement therebetween, and also because of the elimination of fixed pivot points which would cause the locking pin 187 to travel in an arcuate course during its movement.

Such fixed pivot points are replaced by the fulcrum pins 203, 204 over which slide the levers 191, 195. The longitudinal sliding action between the levers 191, 195 is only slight, but because of the clearance in the hole 199 around the stud 197, and the clearance of hole 211 around pin 207, to be described hereinafter, together also with the fact that the slot 209 in the lever 195 clears the shoulder 210 on the stud 205, and also because of the fact that the end of the lever 191 slides in the slot 193 in the pin 187, the movement of the pin 187 becomes a straight line movement instead of following an arcuate path.

Any binding from a side action that might be caused by pin 187 in the hole 188 in the bar 119 is eliminated by the side support provided by lever 195, and lever 191, and the clearance of hole 199 around the pin 197, together with the fact that levers 191 and 195 are free to slide sideways on fulcrum pins 203, 204. It will be seen, accordingly, that levers 191 and 195 have a floating motion between them in both longitudi-

nal and lateral directions so as to maintain the pin 187 free from any binding action in its movement.

In order to guide the vertical movement of the lever 195, a pin 207 is held in the bar 117 and serves as a guide for the lever 195, as well as limiting the longitudinal movement thereof, the lever 195 being provided with a hole 211 for receiving the pin 207. The slot 209 in the lever 195 clears the pin 187, stud 197, and stud 205, and terminates rearwardly of the clearance hole 211.

From the above, it will be seen that when the lever 195 is pressed up to release the pin 187 for freeing the saw carriage assembly, the latter swivels around the stud 144 into the desired angular adjustment. When it is properly adjusted, the saw carriage assembly may be locked against accidental displacement by actuating the rod 173, by means of its handle end 176, this actuating the lever 163 to turn the stud 161, which draws the clamp bar 149 and the bar 119 towards each other by action of the thread 162 on the end of the stud 161 sufficiently to clamp the bars together against the top and bottom surfaces of the locking bar 31. Release thereof is effected by opposite actuation of the rod 173 and lever 163.

Notches 185 may be positioned at angles which are frequently used, so that the saw assembly may be quickly adjusted to such angles with the help of the locking pin 187. Of course, the saw assembly may be locked at any other angle where the pin 187 does not engage one of the notches 185.

The distance between the saw supports 89 and 91 may be adjusted to change the length of movement of the saw or to provide for blades of different lengths. From an inspection of Fig. 9 it will be seen that by loosening the screw 125, the bar 117 carrying the holder 113 may be drawn outwardly until the rear end of the slot 152 strikes the screw 125. During this movement the pin 207 will carry the lever 195 outwardly, as the slot 209 slides over the shoulder 210 of the stud 205, and the lever 195 slides over the pivot 204. When the desired position for the holder 113 is reached the screw 125 is tightened, whereupon the locking mechanism will function as before.

It is believed that the operation of the various parts of the present improved construction will be apparent from the foregoing description, and that no further reference to the operation of the parts needs to be given.

From the foregoing detailed description, it will be understood that the invention is not limited, necessarily, to the specific details of the construction as are herein specifically illustrated and described, as it will be apparent that such details are subject to various modifications which will become apparent readily to one skilled in the art, without departing from the spirit of the invention; and it will be understood, therefore, that it is intended and desired to include within the scope of the invention such modification and changes as may be necessary to adapt it to varying conditions and uses. It is also to be understood that the following claims are intended to cover all of the generic and specific features of the invention herein described, and all statements of the scope of the invention which, as a matter of language, might be said to fall therebetween.

What is claimed is:

1. In a miter box, means for clamping material to be sawed comprising in combination, a curved arm; means for securing each end of said arm to

said miter box; a sleeve journaled in said arm and provided with a pair of opposite apertures; a clamp screw slidably mounted in said apertures; a piston reciprocable in said sleeve, said piston being provided with an elliptical aperture adapted to coincide with the apertures in said sleeve, said aperture being provided at its narrow end with half threads adapted to fit the threads on said clamp screw, said clamp screw being slidable 5 axially through the wide end of said aperture; and means for reciprocating said piston to change the position of said clamp screw in said aperture and so to permit slow or fast adjustment thereof.

2. In a miter box, means for clamping material 10 to be sawed comprising in combination, a curved arm; means for securing each end of said arm to said miter box; a sleeve journaled in said arm and provided with a pair of opposite apertures; a clamp screw slidably mounted in said apertures; a piston reciprocable in said sleeve, said piston being provided with an elliptical aperture adapted to coincide with the apertures in said sleeve, said aperture being provided at its narrow end with half threads adapted to fit the threads 15 on said clamp screw, said clamp screw being slidable axially through the wide end of said aperture; and spring and stop means for controlling reciprocation of said piston to change the position of said clamp screw in said aperture and so to permit slow or fast adjustment thereof.

3. In a miter box, means for clamping material 20 to be sawed comprising in combination, a curved arm; means mounted on said miter box providing a pivot for one end of said arm, said arm being slidable along said pivot means; substantially 25 instantaneously releasable means for

securing the other end of said arm to said miter box; a sleeve journaled in said arm and provided with a pair of opposite apertures; a clamp screw slidably mounted in said apertures; a piston reciprocable in said sleeve, said piston being provided with an elliptical aperture adapted to coincide with the apertures in said sleeve, said aperture being provided at its narrow end with half threads adapted to fit the threads on said clamp screw, said clamp screw being slidable axially 25 through the wide end of said aperture; and means for reciprocating said piston to change the position of said clamp screw in said aperture and so to permit slow or fast adjustment thereof.

4. In a miter box, means for clamping material 30 to be sawed comprising in combination, a curved arm; a pin mounted on said miter box providing a pivot for one end of said arm, said arm being slidable along said pin; spring controlled releasable means for locking the other end of said arm 35 to said miter box; a sleeve journaled in said arm and provided with a pair of opposite apertures; a clamp screw slidably mounted in said apertures; a piston reciprocable in said sleeve, said piston being provided with an elliptical aperture adapted to coincide with the apertures in said sleeve, said aperture being provided at its narrow end with half threads adapted to fit the threads on 40 said clamp screw, said clamp screw being slid- able axially through the wide end of said aperture; and spring and stop means for controlling reciprocation of said piston to change the position of said clamp screw in said aperture and so to permit slow or fast adjustment thereof.

WILLIAM J. PARSONS.
